[57] CLAIM

The ornamental design for an electronic information key, as shown and described.

DESCRIPTION

FIG. 1 is a perspective view of an electronic information key showing my new design;

FIG. 2 is a side elevational view thereof;

FIG. 3 is a bottom plan view;

FIG. 4 is a top plan view;

FIG. 5 is an end elevational view taken from the right hand end thereof;

FIG. 6 is an end elevational view thereof taken from the other end;

FIG. 7 is a perspective view of a second embodiment of an electronic information key showing my new design;

FIG. 8 is a side elevational view thereof;

FIG. 9 is a bottom plan view thereof;

FIG. 10 is a top plan view thereof;

FIG. 11 is an end elevational view from the right hand end thereof; and

FIG. 12 is an end elevational view thereof taken from the other end.
